UNITED STATES PATENT OFFICE.

CHARLES G. STREICH, OF OSHKOSH, WISCONSIN.

BOTTOM DOOR FOR DUMP-WAGONS.

1,144,389.

Specification of Letters Patent. Patented June 29, 1915.

Application filed October 2, 1914. Serial No. 864,553.

To all whom it may concern:

Be it known that I, CHARLES G. STREICH, a citizen of the United States, and resident of Oshkosh, in the county of Winnebago and State of Wisconsin, have invented certain new and useful Improvements in Bottom Doors for Dump-Wagons; and I do hereby declare that the following is a full, clear, and exact description thereof.

- 10 My invention refers to dump wagons of the swinging bottom type and has for its object to provide simple, economical and effective means for obviating the tendency of the bottom door to bind in its swinging movement, provision for eliminating such bind being a peculiarity of the construction of a hinge member, which member also permits the door to swing upon a fixed axis coincident to a closing movement.
- 20 In dump wagons of the swinging bottom door type it has been the practice heretofore to construct the hinge connections between the body of the wagon and the bottom doors with sufficient play to permit the doors when 25 swung downwardly to a dumping position to move upwardly in a vertical position with relation to the dumped load, this loose fit being essential in order to prevent binding of the swinging and vertically reciprocative 30 door member. Hence, in practice, it has been found that with the loose shackle or hinge connections used the play of the pintle member with relation to its knuckle member is such that the doors, when swung to a 35 closing position will frequently bind or not effect a tight joint at their free edges and it is the purpose of my present invention to overcome this objectionable feature and the feature wherein the door is liable to cramp 40 when drawn upward in a vertical direction.

With the above objects in view the invention consists in certain peculiarities of construction and combination of parts as set forth hereinafter with reference to the accompanying drawings and subsequently claimed.

In the drawings Figure 1 represents a rear portion of a dump wagon having hinge members attached thereto for the bottom 50 doors embodying the features of my invention and an anti-friction device made in accordance with my invention that is adapted to engage the wheel-rim or tire when the doors are swung open or vertically lift-

ed from their open position, and Fig. 2, a 55 cross-section of the same, the section being indicated by line 2—2 of Fig. 1.

Referring by characters to the drawings, 1 represents the body of a dump wagon, 2 the rear axle, and 3' one of the rear wheels, 60 it being understood that in practice the vehicle is preferably provided with double bottom doors 3, 3, as indicated in Fig. 2 of the drawings, that are adapted to close at a longitudinal dividing line midway of the 65 body. The doors have secured thereto apertured straps 4 adjacent to their ends and at an intermediate point, in which strap apertures are mounted revoluble bolt-pintles 5, each of which normally rests at the base 70 of a pair of slots 6. These slots are formed in companion rail members 7, that are vertically disposed to constitute part of a bracket 8, each of the same being bolted or otherwise secured to the side walls of the 75 wagon body adjacent to their bottom edges. The base of each bracket slot 6 is in axial alignment with a series of such brackets, whereby the several pintle bolts, under normal conditions, are correspondingly aligned, 80 attention being called to the fact that the pintle bolts are of such diameter as to snugly fit the walls of the slots and, when at rest in the base sockets, their lower circular faces are nested in the corresponding circular 85 bases of the slots, whereby play of the pintles is only had in a vertical direction. The slotted rails 7 are, as stated, vertically disposed and project outwardly from the side walls of the wagon and the sides of the companion rails are tapered upwardly from 90 their base portions.

In order to strengthen the outer free ends of the bottom doors each of the same is provided with an angle-iron reinforcing strap 95 9, which is vertically disposed as shown, and secured to the projecting web of each strap is a bracket 10 formed with apertured ears which are connected by a trunnion 11 and loosely mounted upon the trunnion is a revoluble anti-friction member in the form of a roller 12, the outer face of which roller projects beyond its carrying bracket 10 to form a revoluble rub member adapted to engage the inner face of the juxtaposed wheel-rim 105 or tire. As shown in Fig. 1, the anti-friction roller is of such length that its rear end will come in contact with the tire or rim of

the juxtaposed rear wheel when the door is swung downward, being held in suspension at the base of the rail slots 6.

In practice, after the doors have been 5 swung open, as indicated in dotted lines in Fig. 2, the load is dumped and the side pressure of said load upon the swinging doors will cause the doors to be forced outwardly. This movement is limited by engagement of 10 the anti-friction roller 10 with the wheel-rim or tire near the ground line. The movement of each door is controlled by a runner 13 which is anchored in any suitable manner to the rear portion of the wagon, as shown 15 in Fig. 1. Each runner so anchored is passed through roller guides 13' and intermediate loop guides 13'', with which the free edge of the door is provided. From thence, as shown in Fig. 1, the runner or 20 chain 13 passes upward and over a guide roller 13''' that is suitably supported in a bracket at the forward end of the body and from this point each runner 13 passes over a winding drum 14. Hence when the chains 25 or runners are wound up they will cause the doors to swing to the position as shown in Fig. 2 of the drawings and when the operating mechanism is released the said doors are free to swing downwardly, as shown in 30 Fig. 1. It is obvious that, when the doors are swung open in the position shown in Fig. 1, should it be desired to move the wagon forward clear of the dump, although great pressure of the doors against the rear 35 wheels is had, this pressure will not form a brake for said wheels due to the fact that the rollers 12 will revolve coincident to rotation of said wheels, whereby the vehicle can be drawn clear of the load without exerting unnecessary power and this power under ordinary conditions wherein the anti-friction mechanism is not present is frequently so great as to overtax the draft animals. The doors, when swung to their open 40 position, as shown in Fig. 1, are usually withdrawn or lifted vertically by manipulating the runners 13, whereby said doors are caused to move upward upon the outer faces of the wagon body sides. The longitudinally disposed slots 6 in the rail members 45 7 will permit this movement and the doors will thereby be drawn upwardly and, during the upward lift of the same, it is apparent that the anti-friction rollers 12 will 50 travel upon the curved face of the wheel-rim or tire throughout the movement due to the length of said rollers.

As mentioned in the summing up of the 60 objects of my invention, although the controlling runners for lifting the doors may be centrally disposed with relation to their length, the frictional resistance of the "dump" upon the inner faces of the rollers will frequently cause one end of a door to 65 lift in advance of the opposite end and this

skewing or oblique rise of the doors under ordinary conditions will cause a cramp between the pintle member and the knuckle member, whereby the door is absolutely locked to resist pull of the runner connected thereto. Should this cramping occur in a wagon equipped with rails having tapered sides, as shown, it is obvious, as indicated by the dotted line α , should the forward end of the door lift first, the tapered side walls of 70 the rails will thus present a clearance space for the strap heads and pintle bolts 5, whereby binding of the parts is eliminated and hence, even though the forward end of the door should initially lift in advance of the 75 rear end, there is no bind between the hinge members and the door will eventually be withdrawn to assume a vertical position with the pintles at the top ends of the rail slots. 80

While I have shown a wagon body provided with a series of three bracket members each having a pair of slotted rail members, the side walls of which are tapered upwardly, it is obvious that I may, without departing from the spirit of my invention, use only two or more of such brackets for each door or the brackets may be made with single rail members tapered and slotted in accordance with my invention, under which conditions the head of the strap member may be bifurcated to straddle the rail or it may be set to one side thereof with a pintle extending through the rail slot. 85

It is apparent from the foregoing description that the pintle bolts between their heads are of a length equal to the distance between the outside faces of the rail members at their wide base ends. Thus when the door is lifted, with one end describing an arc relative to the companion pintle, the tilted pintle upon a higher plane will have clearance, due to the converging side walls of the rails, the same result being accomplished by the lift of the knuckle therebetween and as the bolts are loosely mounted within the strap apertures, they constitute rollers in effect to eliminate friction and wear when they travel back and forth in the bracket slots. 100

I claim:

1. The combination with a dump wagon having a body, wheels and a drop-door bottom, a hinge connection between the body and door comprising a pair of vertically disposed spaced rail members each provided with a longitudinally disposed slot, the side walls of the rails being tapered, and a pair of spaced pintle members carried by the door engageable with the rail slots. 105

2. The combination with a dump wagon having a body, wheels and a drop door bottom, a hinge connection between the body and door comprising a pair of upwardly tapered vertically disposed spaced rail members each 110

provided with a longitudinally disposed slot, the base of the slots being curvilinear to form pintle sockets, straps extending from the door, a pair of spaced rounded 5 pintle members loosely mounted in the straps engageable with the rail slots, the pintle members being of a diameter approximately equal to the width of said slots whereby side play between the hinge members is eliminated.

3. The combination with a dump wagon having a body, wheels and a drop door bottom, a hinge connection between the body and door comprising a pair of vertically disposed bracket members fitted to the outer walls of the wagon body, the bracket members each comprising a pair of vertically disposed projecting rails the companion sides of which are tapered upwardly from a

base-line, the said rails being longitudinally 20 slotted upon a common plane, and hinge members secured to the door having a knuckle interposed between each pair of bracket rails, and a pintle extending from each knuckle engageable with the companion rail slots, the pintles being of a length equal to the distance between the outside faces of the companion rails at their base portions.

25 In testimony that I claim the foregoing I have hereunto set my hand at Oshkosh in the county of Winnebago and State of Wisconsin in the presence of two witnesses.

CHARLES G. STREICH.
